(57) **CLAIM**

The ornamental design for a bottle cap as shown and described.

DESCRIPTION

FIG. 1 is a top, front, right perspective view of a bottle cap showing my new design.

FIG. 2 is a bottom, rear, left perspective view thereof.

FIG. 3 is a front view thereof.

FIG. 4 is a rear view thereof.

FIG. 5 is a top view thereof.

FIG. 6 is a bottom view thereof.

FIG. 7 is a left view thereof.

FIG. 8 is a right view thereof; and,

FIG. 9 is a top, rear, left perspective view thereof.

Portions of the bottle cap shown in broken lines form no part of the claimed design.

1 Claim, 9 Drawing Sheets
